WITNESS:

UNITED STATES PATENT OFFICE.

ROBERT IVAN ARMPRIESTER, OF PHILADELPHIA, PENNSYLVANIA.

WALKING TOY.

1,396,087.

Specification of Letters Patent.

Patented Nov. 8, 1921.

Application filed August 13, 1920. Serial No. 403,254.

To all whom it may concern:

Be it known that I, ROBERT IVAN ARMPRIESTER, a citizen of the United States, residing at Philadelphia, in the county of Philadelphia and State of Pennsylvania, have invented new and useful Improvements in Walking Toys, of which the following is a specification.

10 The invention relates to toys and more particularly to walking toys such as dolls and the like and has for an object to provide a toy which may be in the nature of a doll and which is constructed to simulate, more or less the walking of a human being.

15 Among other features the invention comprehends a doll or other toy in which the legs are arranged with respect to the body of the doll so that a forward swinging action of one leg is obtained while the weight 20 of the body is resting on the other leg, thus simulating the walk of a human being.

I am aware that various forms of walking dolls have been used heretofore, but I find in many of these instances the result is not 25 a walk such as would tend to accurately simulate the walk of a person, and furthermore in other instances the walking action is only obtained by the use of the springs and other resilient members which soon 30 wear out and also greatly complicate the structure.

I aim to provide a walking doll for instance in which there are no springs involved and in which the parts are of simple design 35 and construction and effectively coöperate to bring about the desired result.

Still further the invention comprehends a doll in which the arms are preferably arranged relative to the body so that they 40 can be conveniently grasped, affording an effective grip for the operator in manipulating the doll to simulate the walking of a human being.

In the further disclosure of the invention 45 reference is to be had to the accompanying drawings constituting a part of this specification, in which similar characters of reference denote corresponding parts in all the views, and in which,—

50 Figure 1 is a front elevation of the device constructed as a doll, parts being broken away to disclose the underlying structure.

Fig. 2 is a fragmentary side elevation, the joint member and one of the leg portions 55 being shown in section.

Fig. 3 is a horizontal sectional view taken on the line 3—3 in Fig. 1, and

Fig. 4 is a perspective view of one of the joint members removed.

Referring more particularly to the views, 60 the numeral 10 indicates the body of the doll, and 11, the arms, and 12 the legs, the latter being each preferably constructed in two portions, of which the upper portion is indicated by the numeral 12^a and the lower 65 portion by the numeral 12^b. The arms are also preferably constructed in two portions, the upper of which is indicated by the numeral 11^a and the lower portion thereof by the numeral 11^b. The arm portion 11^b 70 is suitably fitted to and hinged to the arm portion 11^a, and the latter is hinged by means of a suitable hinge 13 to the body 10 so that the arm can be swung outward, thus affording a convenient grip for the operator 75 to manipulate the doll. The leg portion 12^b at its upper end is fitted to and hinged to the lower part of the leg portion 12^a and the upper end of the leg portion 12^a is formed 80 with a slot 14 into which is fitted the lower end of a joint member 15. The joint member at substantially its medial portion passes through a slot 16 in the lower part of the body 10 and is mounted to swing in the slot with the upper part of the joint member 85 lying within the body as shown. Suitable blocks 17 are secured within the body and form bearings for a crank 18 having a plurality of off-set portions 19, one of which is off-set from the main longitudinal line of 90 the crank in a directly opposed relation to the other portion. The inner ends of connecting links 20 are mounted to swing on the off-set portions of the crank as shown and the outer end of each connecting link 95 connects with one of the joint members 15 near the upper part thereof. By careful reference to the views, it will be seen that the lower end of each joint member 15 is provided with an extension 21 which is in 100 the nature of a stop member by reason of the fact that when the leg portion 12^a is swung backwardly on the joint member the engagement of the extension 21 with the joint member in the slot 14 limits the rearward swinging movement of the leg portion 105 and this is an essential feature in order to bring about proper operation of the device as will be hereinafter more fully set out. So also the lower end of each joint member 110

has a cut away portion 22 at the front, in order that the leg portion 12^a can readily swing forward without interference from the lower part of the joint member.

- 5 In the operation of the doll to effect a walking action it will be seen that normally the crank 18 is arranged to have one off-set portion extend upwardly and the other off-set portion extend downwardly, the crank 10 being in this position when the legs are substantially straight. In order to effect walking motion of the doll, it is first necessary that the operator grasp and swing upwardly one of the arms into a substantially horizontal position, it being noted that the shoulder joint of the arm is such as to limit the upward swinging movement to substantially the horizontal. By imparting a slight turning movement of the hand to the arm and 15 inclining the doll slightly to one side, the opposite leg will be raised from the floor and by reason of the joint members and crank connection the leg will swing forwardly while the weight of the doll rests 20 upon the other limb. This action will now bring the crank and joint member of the opposite limb into position to effect a similar result thereon when the doll is swung slightly the other way to bring the weight 25 thereof on to the limb which has been moved forward and in this manner the doll will be caused to walk along the floor with but very little effort upon the part of the operator.
- 30 It will be apparent that the particular construction of the joint members and their relationship to the crank, are the prime factors involved in bringing about the operation of the doll so that the legs will effect 35

tively simulate the walk of a human being 40 and it will be clearly understood that I rely particularly upon the joint members and crank connection to effect this result.

It will be obvious that the construction set out may be applied to a doll or any other 45 form of toy in which a walking operation is to be effected and it will be apparent that I do not limit myself particularly to the use of my construction with any particular form of toy and that various slight changes 50 may be made without departing from the spirit of the invention, the scope of which is defined in the appended claim.

Having thus described my invention, I 55 claim—

A walking doll comprising a body having a bottom portion, vertically swingable arms pivoted upon the sides thereof, either arm serving as a handle whereby to effect manipulation of the doll, the bottom portion 60 of the body being formed with spaced slots, lever members extending through said slots and pivoted at the lower end of the body, a horizontally disposed shaft within the body formed with oppositely extending crank 65 portions, links pivotally connected with the respective crank portions and jointed legs pivoted upon the lower ends of said lever members, said legs being provided with knee joints, the upper ends of the legs being 70 slotted for the reception of the lower ends of said lever members, said slots defining abutment shoulders, and the lower ends of the levers being formed with extensions engageable with said shoulders whereby to 75 limit swinging movement of the legs.

In testimony whereof I affix my signature.

ROBERT IVAN ARMPRIESTER.
